CONVERSION OF HYDROCARBON OILS

Richard F. Trow, Port Arthur, Tex., assignor to
The Texas Company, New York, N. Y., a cor-
poration of Delaware

Application May 4, 1933, Serial No. 669,301

8 Claims. (Cl. 196—49)

This invention relates to the pyrolytic conversion of hydrocarbon oils, more particularly petroleum oils, to oils of lower boiling points.

My invention has for an object the provision of a process for converting hydrocarbon oils which is capable of producing a high yield of light distillate of high antiknock value and a low yield of heavy distillate or fuel oil from a dirty stock, that is to say, a stock which cannot be subjected to a drastic cracking operation producing a high yield of gasoline per pass without excessive coke formation.

My invention has for further objects such additional improvements in operative advantages and results as may hereinafter be found to obtain.

My invention is especially applicable to an operation conducted for the purpose of converting hydrocarbon oils to oils of lower boiling point in which a stock is subjected to cracking conditions of temperature and pressure, as for example, while passing through a heating coil, the cracked products being delivered to one or more enlarged reaction vessels or stills from which vapors and residual oils in liquid form are separately withdrawn, and more especially to operations in which liquid is withdrawn from the reaction vessel or vessels at a rate sufficient to prevent liquid from accumulating within the reaction vessel or vessels and to prevent digestion of liquid within the same, while permitting digestion of vapors therein at a cracking temperature.

My invention contemplates heating a charging stock, such, for example, as a dirty gas oil or a reduced crude resulting from a previous topping operation, to a moderate cracking temperature and soaking the heated stock, preferably in a separately fired soaking coil, to break or reduce the viscosity of the stock without causing deposition of coke to an undesirable extent, and discharging the viscosity broken stream into a distilling zone supplied with hot vapors produced elsewhere in the system. In the distillation zone, the more volatile constituents of the viscosity-broken stream are vaporized and the resultant vapors, together with other vapors from the distillation zone, are fractionated or dephlegmated, for example, by indirect contact with a stream of relatively cool charging stock or by refluxing with a suitable oil, to recover therefrom a clean gas-oil fraction suitable for drastic cracking, preferably in the vapor phase at a temperature of, for example, 900° to 1050° F., and a light distillate comprising naphtha or gasoline.

My invention further contemplates the cracking of the clean gas-oil fraction in the manner

indicated, that is to say, at relatively high temperature and preferably in the vapor phase, the cracked products being delivered to one or more enlarged reaction vessels or stills from which unvaporized or residual liquid is preferably withdrawn at a rate sufficient to prevent accumulation of liquid in the reaction vessel or vessels. The residual liquid thus withdrawn may be treated for the recovery of the more volatile constituents thereof, while the vapors pass to the distillation zone where they are brought into contact with the viscosity-broken charging stock.

Unvaporized oil collecting within the distillation zone may be delivered to one or more of the reaction vessels or stills, either directly or by being commingled with the stream of cracked products entering the same from the high-temperature or vapor-phase cracking coil.

My invention further contemplates cooling a portion of the clean gas oil or other intermediate fraction recovered by fractionation and dephlegmation of the vapors as set forth hereinabove, and the delivery of the resultant cool oil to the distillation zone for purposes of dephlegmation and to prevent coking.

With regard to the conditions under which the viscosity breaking of the charging stock is carried out, it may be said that, in general, the temperature employed will be sufficient to produce a material reduction of the viscosity of the charging stock without causing the deposition of coke to a material extent and to effect a limited amount of cracking per pass, for example, from 6% to 8% of gasoline per pass and at the most not over 12% of gasoline per pass. The effect of this treatment is, however, to make it possible ultimately to obtain larger yields of valuable light cracked distillate from a dirty charging stock without excessive coke formation.

In order that my invention may be clearly set forth and understood, I now describe, with reference to the drawing accompanying and forming part of this specification, a preferred manner in which my invention may be practiced and embodied. In this drawing,

The single figure is a more or less diagrammatic elevational view of apparatus for accomplishing the conversion of hydrocarbon oil to oils of lower boiling point in accordance with my invention.

In the drawing, there is illustrated a furnace 1 having a high-temperature heating coil 2 and an economizer coil 3, and also a separately-fired furnace 4 having a heating coil 5.

In the present instance there are provided

three enlarged reaction vessels or stills 6, 7, and 8, although it will be readily understood by those skilled in the art that the number of such vessels or stills may be varied in accordance with the requirements of individual instances. The distillation zone referred to hereinabove is located within a suitable vessel 10 having baffles 11, and the dephlegmation and fractionation of vapors removed from the vessel 10 is carried out in a suitable fractionating tower 12 which may be provided with a plurality of gas-and-liquid-contact trays or the like, shown diagrammatically at 13. Many specific forms of suitable trays are known in the art and no particular type need be described here in detail.

Further dephlegmation of vapors not condensed in the fractionating tower 12 may be accomplished in a dephlegmator 14 provided with a heat-exchange coil 15. As shown, the apparatus additionally comprises the condenser 16, a gas separator 17, cooling coils 18 and 19 and various conduits or transfer lines, valves and pumps which will be referred to hereinbelow.

In practicing my invention, a charging stock, such, for example, as a dirty gas oil, a reduced crude or a mixture thereof, is withdrawn from a source (not shown) through a conduit 21 by means of a pump 22 and may initially be passed in the manner indicated in the drawing through the heat-exchange coil 15, where, by indirect contact with vapors passing through the dephlegmator 14, the temperature of the charging stock may be brought to from 400° to 450° F. It will, however, be understood that if the charging stock is already in a heated condition there will be no advantage in passing the stock through the heat-exchange coil 15 and this step may then be omitted. In the latter event, however, it is desirable to supply a suitable reflux oil to the fractionating tower 12.

The heated charge oil then passes under elevated pressure through a conduit 23 to the economizer coil 3 within the furnace 1, where the temperature of the charging stock is raised to a point sufficient to support a moderate cracking or viscosity-breaking effect, for example, from 820° to 880° F., and preferably about 860° F.

The heated charging stock flows from the economizer coil 3 through a conduit 24 to the soaking coil 5 located within the furnace 4. Preferably, merely sufficient heat is provided in the furnace 5 to maintain the charging stock within the desired temperature range in order to complete the viscosity-breaking operation. However, if for any reason the oil should leave the economizer coil 3 at a temperature lower than the desired cracking temperature, sufficient heat may be supplied to the tubes forming the first portion of the coil 5 through which the stream passes to raise the oil to the desired temperature, and the oil is then soaked for a sufficient time at this temperature in the remaining portions of the coil 5.

The viscosity-broken stream leaving the coil 5 then passes through a transfer line 25 to the distillation vessel 10, which it enters at an intermediate point.

Within the vessel 10, the viscosity-broken stream is subjected to direct contact with hot vapors from the still 8 entering the lower portion of the vessel 10 through a conduit 26, and a combined volatilizing and dephlegmating effect occurs, resulting in the vaporization of the more volatile constituents of the viscosity-broken stream. The combined vapors reaching the top

of the distillation vessel 10 pass through a vapor line 27 to the lower part of the fractionating tower 12, where dephlegmation is carried out to a sufficient extent to produce a liquid fraction comprising a gas oil or the like which collects in the lower portion of the fractionating tower 12 and is withdrawn through a conduit 28. A portion of this gas-oil fraction may be withdrawn through a branch conduit 29 having a valve 31 and after being cooled in the cooling coil 10 18 may be delivered by means of a pump 32 and a reflux line 33 to the upper part of the distillation vessel 10 in sufficient amount to provide a limited dephlegmation of the vapors within the latter and to prevent the formation of coke on the baffles 11.

The remaining portion of the clean gas oil fraction or recycle stock removed from the bottom of the fractionating tower 12 is withdrawn through a branch conduit 34 having a valve 35 and 20 is delivered by means of a pump 36 and a conduit 37 to the vapor-phase cracking coil 2 located in the furnace 1, where it is heated to a temperature sufficient to effect vapor-phase cracking, preferable at a high rate of cracking per pass, for example 25% or more. Thus I may employ temperatures of from 900° to 1000° F. and preferably about 975° F. The cracked products then pass through a transfer line 39 which may be provided as shown with a pressure-reducing valve 41 to the upper part of the still 6. Within the still 6 a separation of vapors and liquid occurs, the vapors, and it may be a small amount of liquid oil, passing through a conduit 42 into the adjacent still 7. A further separation occurs in 35 the latter and the vapors pass to the third still 8 through an overhead conduit 43.

As recited hereinabove, unvaporized liquids which tend to collect in the stills, 6, 7, and 8 are withdrawn from the latter by means of drain conduits 46, 47, and 48, having float-operated valves 51, 52, and 53, respectively, at rates sufficient to prevent accumulation of liquid within the vessels or stills 6, 7, and 8. Preferably, merely enough liquid is permitted to collect within the 45 vessels 6, 7, and 8 to form a seal to prevent escape of vapors from the bottoms thereof. The residual oil or tar thus withdrawn is preferably delivered through a conduit 53a to a far stripper 59 to be described more fully hereinbelow.

The unvaporized portion of the viscosity-broken stream delivered to the distillation vessel 10, together with any condensate obtained from the vapors entering the distillation vessel 10 through a conduit 26, is withdrawn from the lower part 55 of the distillation vessel 10 through a conduit 55 and delivered by means of a pump 56 through a conduit 57 having a valve 58 to the transfer line 39, or it may be delivered directly to the stills 6, 8, and 7. The residual oil thus withdrawn from 60 the bottom of the distillation vessel 10 may have a high temperature, for example around 850° F., and in treating certain stocks, a portion of the stream leaving the pump 56 may be by-passed through a line 61 having a valve 63 to the cooler 65 19 and thence to the inlet side of the pump 56. In this instance, sufficient cooling is effected in the cooler 19 to reduce the temperature of the oil reaching the pump 56 to, for example, around 800° F. or even lower.

In the preferred method of operation, the introduction of combined condensate and residual portions of the charging stock, whether cooled or not, to the transfer line 39, is so regulated as to maintain a temperature of from about 870° to 75

about 930° F. in the stills 6, 7, and 8, maintenance of this temperature range facilitating the withdrawal of liquid from the stills 6, 7, and 8 and the maintenance of "low liquid level" conditions therein.

The uncondensed vapors leaving the dephlegmator 14 pass through a vapor line 65 to the condenser 16 where they are cooled in the usual manner, the cooled products then passing through a line 66 to the separator 17. Gas and any uncondensed vapors are removed from the separator 17 through a conduit 67 having a valve 68, while light cracked distillate is removed from the separator 17 through a line 69. A portion of this condensate may be returned through a branch conduit 71 having a valve 72 and a pump 73 to the upper part of the fractionating tower 12 as a reflux, while the remaining portion or it may be all of the condensate from the separator 17 passes through a conduit 14 having a valve 75 to storage or to suitable apparatus for effecting stabilization thereof.

The pressures maintained within the system may vary considerably but in general the pressures in the coils 2, 3 and 5 are maintained within a suitable range, for example, from 200 to 600 pounds per square inch. While similar pressures may be maintained throughout the system, it is ordinarily preferred to maintain somewhat lower pressures, for example, from 150 to 350 pounds per square inch, in the stills 6, 7, and 8, the distillation vessel 10 and the fractionating tower 12. In a modified form of my invention the pressure in the dephlegmator 10 and fractionating tower 12 may be reduced to 150 pounds per square inch, or even lower, by means of a pressure-reducing valve 80 located in the conduit 26.

As has been stated hereinabove the liquid withdrawn from the stills 6, 7, and 8 is preferably passed through a conduit 53a to a tar stripper 54. The tar stripper 54 may be varied in design but in the preferred instance illustrated it comprises a flash chamber 81 having baffles 82 and a fractionating section 83 having suitable plates or trays 84. The chamber 81 and the fractionating section 84 are separated by a trap-out tray 85 and the upper portion of the fractionating section 84 is provided with a reflux inlet line 86.

The liquid withdrawn from the stills 6, 7, and 8 in this instance passes through the conduit 53a wherein is located a pressure-reducing valve 87 by means of which the oil is reduced in pressure as it passes into the flash chamber 81. The lower boiling constituents of the oil are thereby liberated in vapor form and passed upward into the fractionating section 83 through a vapor line 88 while heavy residual portions of the oil are withdrawn from the bottom of the flash chamber 81 through a conduit 90 having a valve 91 and preferably leading through a cooler 92 to fuel oil storage facilities (not shown).

By means of reflux introduced through the line 88 or by cooling effected in any other suitable manner the vapors passing through the fractionating section 83 or the tar stripper 54 are subjected to fractional condensation to such an extent as to effect the separation in liquid form of a heavy gas oil fraction which is withdrawn from the trap-out tray 85 through a conduit 93 having a pump 94 and branches 95 and 96 having valves 97 and 98, respectively. This heavy gas oil withdrawn from the trap out tray 85 may be withdrawn from the system through the conduit 95 or may be delivered through the conduit 96 and the line 23 to the inlet of the coil 3, being thus

combined with the stream of preheated charging stock being delivered to the coil 3 for treatment therein.

The vapors remaining uncondensed at the top of the fractionating section 83 of the tar stripper 54 pass through a conduit 97 to a condenser 98 where they are cooled to effect a condensation of normally liquid constituents, the operation preferably being conducted to recover at this point a distillate comprising either heavy naphtha constituents or light gas oil constituents or a mixture of these. The mixture of uncondensed gases and condensate then passes through a conduit 99 to a gas separator 101 having a valved outlet 102 through which uncondensed gases escape. The 10 condensate passes out of the separator 101 through a conduit 103 having a pump 104, by means of which it may be partly returned through the conduit 86 wherein is located a valve 105 to the tar stripper 54 as reflux. The remaining portion of the condensate recovered in the separator 101, or it may be all of this condensate, is preferably delivered by the pump 104 through the conduit 103 and a conduit 106 having a branch 107 wherein is located a valve 108, 25 to the conduit 37 where it is commingled with gas oil recycle stock withdrawn from the bottom of the fractionating tower 12 and being delivered to the cracking coil 2.

In an alternative method of procedure, a portion or all of the condensate withdrawn from the separator 101 may be returned through conduits 103 and 106 and a branch conduit 109 having a valve 110 to the fractionating tower 12 for use as reflux therein.

It will be obvious to those skilled in the art that my invention is not limited to the specific details of the illustrative example or examples set forth and described hereinabove but may variously be practiced within the scope of the claims herein- 40 after made.

What I claim is:

1. The process of converting hydrocarbon oil into oils of relatively low boiling points which comprises heating a charge oil to a mild cracking temperature and soaking the heated oil substantially without reduction of temperature in a primary cracking zone to reduce the viscosity of the oil, passing the viscosity-broken products directly to a distillation zone into direct contact 45 with hot vapors produced in the system, thereby vaporizing lighter fractions of said viscosity-broken products, passing vapors from said distillation zone to a fractionating zone and dephlegmating said vapors to recover therefrom a 50 light distillate and a heavier recycle stock fraction, subjecting said recycle stock to relatively drastic cracking conditions in a separate cracking zone, discharging the cracked products into the first of a plurality of enlarged reaction vessels 55 arranged in series in each of which separation of vapors from liquid products of reaction occurs, conducting separated vapors from one reaction chamber to the others in succession and from the last reaction chamber to said distillation zone, 60 separately withdrawing separated liquid from each of said reaction chambers, withdrawing residual oil from said distillation stage and directing it to said series of enlarged reaction vessels.

2. The process of converting hydrocarbon oil 70 into oils of relatively low boiling points which comprises heating a charge oil to a cracking temperature of the order of 820° F.-880° F. and soaking the heated oil substantially without reduction of temperature in a primary cracking zone 75

to reduce the viscosity of the oil and effect a cracking per pass into gasoline constituents not exceeding 12%, introducing the resultant viscosity-broken products directly into a distilling zone 5 wherein said products are brought into contact with hot vapors produced in the system, thereby vaporizing lighter fractions of the viscosity broken products, dephlegmating the evolved vapors from said distillation zone to recover 10 therefrom a light distillate and a heavier condensate, subjecting said heavier condensate to heating to effect a high rate of cracking per pass in a separate cracking zone and directing the cracked products into an enlarged reaction zone, 15 conducting residue from said distillation zone into said reaction zone, maintaining a temperature therein of the order of 870°-930° F., withdrawing liquid constituents from said reaction zone at a rate adequate to prevent accumulation of 20 liquid therein passing vapors from said reaction zone to a second reaction zone wherein the vapors are maintained at cracking temperature to effect further cracking and directing vapors from said second reaction zone.

25 3. The process of converting hydrocarbon oil into oils of relatively low boiling points which comprises passing cycle condensate formed in the process through a high temperature heating coil wherein the condensate is heated at temperatures 30 of the order of 900° F.-1050° F. to subject the oil to a high rate of cracking per pass, discharging the products from said heating coil into an enlarged reaction zone maintained under cracking conditions and wherein separation of vapor from 35 liquid occurs, withdrawing liquid constituents from said reaction zone at a rate adequate to prevent the accumulation of liquid therein, passing only the separated vapors into a second reaction zone wherein the vapors are maintained at cracking temperature to effect further cracking, directing vapors from said second reaction zone to a distilling zone, heating charging stock in a primary cracking zone to a cracking temperature of the order of 820° F.-880° F. under 40 conditions to effect a cracking per pass into gasoline constituents of about 6%-8% and effect a reduction in the viscosity of the charging stock, delivering the viscosity-broken products directly to said distilling zone into contact with afore- 45 said separated vapors introduced thereinto to effect distillation of the viscosity-broken products and condensation of a portion of said separated vapors, withdrawing from said distilling zone a liquid residue comprising residual constituents of said viscosity-broken products and 50 directing said liquid residue to said enlarged reaction zone wherein it is in contact with the heated products discharged thereinto from the said high temperature heating coil and subjecting vapors evolved from said distilling zone to fractionation to separate out a light distillate and a heavier condensate constituting the cycle condensate passed to the cycle condensate heating coil.

55 4. The process of converting hydrocarbon oil into oils of relatively low boiling points which comprises passing cycle condensate formed in the process through a high temperature heating coil to subject the condensate to a high rate 60 of cracking per pass, discharging the products from said heating coil into an enlarged reaction zone maintained under cracking temperatures of the order of 870° F.-930° F. and wherein separation of vapor from liquid occurs, passing only 65 the separated vapors into a second reaction zone

wherein the vapors are maintained at cracking temperature to effect further cracking, directing vapors from said second reaction zone to a distilling zone, heating charging stock in a primary cracking zone to a cracking temperature of the order of 820° F.-880° F. under conditions to effect a cracking per pass into gasoline constituents of about 6%-8% and effect reduction in the viscosity of the charging stock, delivering the viscosity-broken products directly to said distilling zone into contact with aforesaid separated vapors introduced thereto to effect distillation of the viscosity-broken products and condensation of a portion of said separated vapors, withdrawing from said distilling zone a liquid residue comprising residual constituents of said viscosity-broken products and directing said liquid residue to said enlarged reaction zone wherein it is in contact with the heated products discharged thereinto from the said high temperature heating coil, withdrawing liquid from said enlarged reaction zone at a rate adequate to prevent the accumulation of liquid therein and subjecting vapors evolved from said distilling zone to fractionation to separate out a light distillate and a heavier condensate constituting the cycle condensate passed to the cycle condensate heating coil.

5. Apparatus for cracking hydrocarbon oils that comprises a cracking still, a distilling chamber adapted to receive vapors from the cracking still, a fractionating tower adapted to receive vapors from the distilling chamber and separate out condensate therefrom, a furnace formed to provide a main heating section and an economizer section, a high temperature cracking coil located in the main heating section of the furnace, means for conducting condensate from the fractionating tower to the high temperature cracking coil, a transfer line for conducting the products from the high temperature cracking coil to the cracking still, a low temperature cracking coil located in the economizer section of said furnace, means for introducing charging stock to said low temperature cracking coil, a soaking coil adapted to receive the products from said low temperature cracking coil, means independent of said furnace for maintaining the soaking coil at a cracking temperature, means for conducting products from the soaking coil to said distilling chamber and means for conducting liquid from the distilling chamber to said cracking still.

6. Apparatus for cracking hydrocarbon oils that comprises a cracking still, fractionating means for separating out a condensate from vapors evolved from the cracking still, a furnace formed to provide a main heating section and an economizer section, a high temperature cracking coil located in the main heating section of the furnace, means for conducting condensate from the fractionating means to the high temperature cracking coil, a transfer line for conducting the products from the high temperature cracking coil to the cracking still, a low temperature cracking coil located in the economizer section of said furnace, means for introducing charging stock to said low temperature cracking coil, a soaking coil adapted to receive the products from said low temperature cracking coil, means independent of said furnace for maintaining the soaking coil at a cracking temperature and means for conducting products from the soaking coil to the cracking still.

7. In the conversion of hydrocarbon oil into oils of lower boiling points wherein hydrocarbon oil is subjected to cracking in an enlarged re-

action zone where separation of vapor from liquid residue occurs and wherein the liquid residue is subjected to flash distillation in a flashing zone, the process that comprises heating charging stock in a primary cracking or viscosity-breaking coil to a cracking temperature to effect a reduction in the viscosity thereof, delivering the viscosity-broken products into a distilling zone, passing vapors from said enlarged reaction zone into said distilling zone into contact with said viscosity-broken products therein to effect distillation of the viscosity-broken products and condensation of a portion of said vapors, subjecting the remaining vapors to fractionation to separate out a light distillate and a cycle condensate, passing said cycle condensate to a high temperature cracking coil wherein the oil is subjected to a relatively high cracking temperature to effect a high rate of cracking per pass and directed thence into aforesaid enlarged reaction zone, subjecting the vapors evolved in the flashing zone to fractionation to separate out a lighter fraction and heavier fraction thereof, directing the heavier fraction to said viscosity-breaking coil and passing the lighter fraction to said high temperature cracking coil.

8. In the conversion of hydrocarbon oil into oils of lower boiling points wherein hydrocarbon oil is subjected to cracking in an enlarged reaction zone where separation of vapor from liquid residue occurs and wherein the liquid residue is

subjected to flash distillation in a flashing zone, the process that comprises heating charging stock in a primary cracking or viscosity-breaking coil to a cracking temperature to effect a reduction in the viscosity thereof, delivering the viscosity-broken products into a distilling zone, passing vapors from said enlarged reaction zone into said distilling zone into contact with said viscosity-broken products therein to effect distillation of the viscosity-broken products and condensation of a portion of said vapors, subjecting the remaining vapors to fractionation to separate out a light distillate and a cycle condensate, passing said cycle condensate to a high temperature cracking coil wherein the oil is subjected to a relatively high cracking temperature to effect a high rate of cracking per pass and directed thence into aforesaid enlarged reaction zone, withdrawing from said distilling zone a liquid residue comprising residual constituents of said viscosity-broken products and directing said liquid residue to said enlarged reaction zone wherein it is in contact with the heated products discharged thereinto from said high temperature cracking coil, subjecting the vapors evolved in the flashing zone to fractionation to separate out a lighter fraction and heavier fraction thereof, directing the heavier fraction to said viscosity-breaking coil and passing the lighter fraction to said high temperature cracking coil.
